SOLE PLATE FOR AN ELECTRIC IRON

Henry J. Talge, Kansas City, Mo., assignor to
John C. Hockery, Kansas City, Mo., as trustee

Application August 27, 1952, Serial No. 21,203

Term of patent 14 years

(Cl. D49—6)

To all whom it may concern:

Be it known, that I, Henry J. Talge, a citizen of the United States, residing in Kansas City, in the county of Jackson and State of Missouri, have invented a new, original, and ornamental Design for a Sole Plate for an Electric Iron, of which the following is a specification, reference being had to the accompanying drawing, forming part thereof, in which

Fig. 1 is a side elevational view of a sole plate for an electric iron, embodying my new design; and

Fig. 2 is a bottom plan view thereof.

The dotted line showing is for illustrative purposes only.

I claim:

The ornamental design for a sole plate for an electric iron, as shown and described.

HENRY J. TALGE.
